COMBINED MOTION PICTURE PROJECTOR AP-
PARATUS, FILM EDITOR, FILM SPLICER, AND
CARRYING CASE THEREFOR

William Castedello and Edward K. Kaprelian,
Plainville, Conn.

Application April 13, 1954, Serial No. 29,975

Term of patent 7 years

(Cl. D61—1)

To all whom it may concern:

Be it known that we, William Castedello and Edward K. Kaprelian, both citizens of the United States of America, residing in Plainville, county of Hartford and State of Connecticut, have invented a new, original, and ornamental Design for a Combined Motion Picture Projector Apparatus, Film Editor, Film Splicer, and Carrying Case Therefor, of which the following is the specification, reference being had to the accompanying drawings, forming a part thereof.

Fig. 1 is a perspective view of a combined motion picture projector apparatus, film editor, film splicer, and carrying case therefor shown in closed position and showing our new design;

Fig. 2 is a front perspective view thereof shown in non-operating position, the film splicer being omitted and the cover portion of the carrying case removed therefrom;

Fig. 3 is a front perspective view thereof, taken on an enlarged scale, shown in operating position, the cover portion of the carrying case being omitted therefrom.

The dominant feature of our design resides in the portions shown in full lines.

We claim:

The ornamental design for a combined motion picture projector apparatus, film editor, film splicer, and carrying case therefor, as shown and described.
